LOCKING MECHANISM FOR CLOSURE
MEMBERS

Charles L. Brown, Jr., Stamford, Conn., assignor
to Electrolux Corporation, New York, N. Y., a
corporation of Delaware

Application May 19, 1939, Serial No. 274,567

6 Claims. (CL 292—20)

My invention relates to locking mechanism for closure members and more particularly to locking mechanism for a closure member for a vacuum cleaner casing of the type having a unit pulled around on a supporting surface by a hose.

An object of my invention is to provide an improved closure member with a locking mechanism of simple construction which may be readily manufactured and assembled.

A further object of my invention is to provide an improved locking mechanism for a closure member which will withstand the force transmitted through the closure member in moving it about.

What I consider to be novel and my invention may be better understood by reference to the following specification and appended claims when considered in connection with the accompanying drawings, in which

Fig. 1 is a side view of a vacuum cleaner, broken away in part, and embodying my improved closure member;

Fig. 2 is an end view of the vacuum cleaner;

Fig. 3 is an enlarged sectional view taken along the line 3—3 of Fig. 2;

Fig. 4 is an enlarged detailed view in section taken along the line 4—4 of Fig. 3, showing the locking mechanism in a locking position;

Fig. 5 is a view similar to Fig. 4 with the locking mechanism disengaged; and

Fig. 6 is a perspective view with the cover of the closure member broken away in part to show the locking mechanism.

Referring to Fig. 1, 10 indicates a vacuum cleaner casing in which a dust separating member 11 and a fan 12, driven by an electric motor 13 are located. Dust separating member 11 is secured in an opening 14 of casing 10 by a closure member 15. Closure member 15 is provided with an inlet opening 16 in which a flexible hose 17 is detachably secured. A cleaning tool 18 is connected to the flexible hose 17 with or without an interposed rigid tubular member 19. Casing 10 is provided with an exhaust opening 20. As best indicated in Fig. 3, dust separating member 11 is provided with a ring 21 having an outwardly extending flange 22 covered by a flexible gasket 23. Flange 22 and gasket 23 rest on a recessed seat 24 provided adjacent the opening 14 of casing 10. Closure member 15 secures dust separating member 11 in casing 10 and provides a passage 25 from the inlet opening 16 to the interior of the dust separating member 11.

In the operation of the vacuum cleaner, the

casing 10 usually is located centrally of the surface being cleaned. The area of the surface surrounding the casing 10 is traversed with the cleaning tool 18. When it is desired to clean another area remote from the casing 10, the casing 10 is moved by pulling on the hose 17. The force necessary for moving the casing 10 is transmitted from the hose 17 to the casing 10, through the closure member 15. The closure member 15 performs the function of transmitting this force for moving the casing 10, in addition to its function of securing the dust separating member 11 in the casing and permitting its periodical removal for emptying the dust collected therein. Closure member 15 is provided with a back plate 26 with boss receiving openings 27. Two bosses 28 extend forwardly from the casing 10 and from opposite sides of the opening 14 into the boss receiving openings 27 of the plate 26. Two radially extending springs 29 are loosely held in plate 26 in slots 30 formed in the two plates 31. The inner ends of the springs 29 enter a central recess 32 in the plate 26. The outer ends of the springs 29 are guided by upstanding ears 33 formed in plates 34 secured to the plate 26. The two springs 29 are arched longitudinally with their greatest height nearer their inner ends. A cam 35 is pivotally secured between plates 31 by a pivot pin 36. Cam 35 is movable in a plane 30 perpendicular to the springs 29 by a handle 37 extending outwardly through an opening 38 in a cover 39 secured to plate 26. Cam 35 has beveled edges 35' at each side. A finger recess 40 is provided in cover 39 for grasping handle 37. When the handle 37 is in the position indicated in Fig. 3, the springs 29 are depressed with their outer ends in engagement with the bosses 28. The ends of springs 29 in engagement with the bosses 28 produce a force holding the closure member 15 in tight engagement with the casing 10, preventing the closure member from being pulled away from the casing 10 by any force transmitted through the closure member 15, in moving the casing 10 around on its supporting surface. When the handle 37 is moved in a direction away from the closure member 15, cam 35 is rotated on pivot pin 36 in a counter-clockwise direction, looking from the right, releasing the springs 29, and permitting them to assume free positions with the outer ends withdrawn from engagement with the boss 28. With the springs 29 in this position, the closure member 15 may be withdrawn from the casing 10 to permit the removal of the dust separating member

11. The plate 26 is provided with strengthening ribs 41.

In the manufacture of the closure member 15, the plate 26 is formed in a casting operation with the plates 31 formed integrally therewith. The two guide plates 34 are formed with the upstanding ears 33 and secured to the plate 26. The two springs 29 of arched shape are located in position on the plate 26. The cam 35 with the handle 37 formed integrally therewith is secured between the plates 31 by pivot pin 36. The cover 38 which is preferably formed in a stamping operation, to conform in shape with the general shape of the casing 10, is secured to the plate 26 for covering the locking mechanism.

What I claim is:

1. A locking mechanism for a closure member including an arched spring, a cam engaging the arched portion of said spring and pivoted for movement in a plane perpendicular to said spring, and a handle connected to said cam for rotating said cam to one position depressing said spring and moving said spring outwardly in a radial direction into locking position.

2. A locking mechanism for a closure member including a plate having boss receiving openings, two radially extending springs arched longitudinally, a cam pivotally connected to said plate at the juncture of said springs for movement in a plane perpendicular to said springs, and a handle connected to said cam for rotating said cam to a locking position depressing said springs and moving the springs outwardly in a radial direction to engage bosses entering the boss receiving openings of said plate.

3. A locking mechanism for a closure member including a plate, a plurality of arched resilient members loosely carried by said plate, a cam engaging said resilient members pivotally con-

nected to said plate for movement in a plane perpendicular to said plate, and a handle connected to said cam for moving said cam to depress said resilient members and move said members outwardly into locking position.

4. A locking mechanism for a closure member including a plate having a central recess, an arched resilient member loosely carried by said plate having one end located in said recess and the other end positioned adjacent the outer edge of said plate, a cam engaging said member pivotally connected to said plate for movement in a plane perpendicular to said plate, and a handle connected to said cam.

5. A locking mechanism for a closure member including a plate having a central recess, two arched resilient members secured to said plate with ends located in said recess, the outer ends of said members positioned adjacent the periphery of said plate, and a cam pivotally secured to said plate between said members and rotatable to deform said members and move the outer ends of said members into locking position.

6. A locking mechanism for a closure member including a plate having boss receiving openings and a centrally disposed recess, two radially extending springs arched longitudinally having their inner ends seated in said recess and their outer ends positioned adjacent said boss receiving openings, a cam pivotally connected to said plate at the juncture of said springs for movement in a plane perpendicular to said springs to depress the springs and move their outer ends into engagement with bosses entering said boss receiving openings, and a handle connected to said cam for rotating said cam from a position depressing said springs to a position releasing said springs.

CHARLES L. BROWN, JR.
